US0D1110510S

(12) **United States Design Patent** (10) **Patent No.:** **US D1,110,510 S**
(45) **Date of Patent:** **** Jan. 27, 2026**

(54) **URINARY INCONTINENCE TREATMENT DEVICE**

(71) Applicant: **CERAGEM CO., LTD.**, Cheonan-si (KR)

(72) Inventor: **Jung Hwan Song**, Cheonan-si (KR)

(73) Assignee: **CERAGEM CO., LTD.**, Cheonan-si (KR)

(**) Term: **15 Years**

(21) Appl. No.: **29/913,577**

(22) Filed: **Oct. 5, 2023**

(30) **Foreign Application Priority Data**

Apr. 13, 2023 (KR) 30-2023-0014139

(51) **LOC (15) Cl.** **24-02**

(52) **U.S. Cl.**

USPC **D24/186**

(57) **CLAIM**

The ornamental design for a urinary incontinence treatment device, as shown and described.

DESCRIPTION

FIG. 1 is a perspective view of the treatment device;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the broken lines are for the purpose of illustrating portions of the urinary incontinence treatment device which forms no part of the claimed design.

1 Claim, 7 Drawing Sheets
